UNITED STATES PATENT OFFICE.

JOHN STOERTZENBACH, OF PEEKSKILL, NEW YORK, ASSIGNOR TO
WILLIAM M. CRANE COMPANY, OF NEW YORK.

DESIGN FOR A GAS COOKING-RANGE.

SPECIFICATION forming part of Design No. 34,507, dated May 14, 1901.

Application filed April 1, 1901. Serial No. 53,968. Term of patent 7 years.

To all whom it may concern:

Be it known that I, JOHN STOERTZENBACH, a citizen of the United States, residing at Peekskill, in the county of Westchester and State of New York, have invented and produced a new and original Design for a Gas Cooking-Range, of which the following is a specification, reference being had to the accompanying drawing, forming part hereof.

In the drawing I have shown a perspective view of a range embodying my design, the feature of which is the configuration and ornamentation.

A indicates the base-section, having the legs B and provided with the surface ornamentation extending down upon the legs.

The body portion of the range is generally rectangular, the front portion of which is comprised in the main of the doors C and D.

The lower door C is substantially square in outline and is provided with the scroll-and-leaf ornamentation in relief, which is symmetrically arranged about a substantially semicircular panel E, centrally located in the general direction of one of the diagonals of the door. A prominent feature of the scroll-

work on the door C is the radially-ribbed spiral F, which extends from the concaved side of the panel E downwardly and laterally in a convolute form to a point near the center of one side of the door. The upper door D has an elongated rectangular form and is provided with the scroll ornaments arranged, as shown, about the open lattice-work panels G.

Arranged at the sides of the doors C and D are upright front portions H, having leaf-like ornamentations, as shown.

The top of the range is formed of the sections I, J, and K, the central section I having suitable grated openings overlying the burners and the side sections J and K having the open scrollwork, as shown.

What I claim, and desire to secure by Letters Patent, is—

The design for a gas cooking-range shown and described.

Signed this 26th day of March, 1901.

JOHN STOERTZENBACH.
